BOOKKEEPING MACHINE

Ernst Vilhelm Nyberg, Stockholm, Sweden, assignor, by mesne assignments, to Ekonomiregister Inc., New York, N. Y., a corporation of New York

Application November 30, 1937, Serial No. 177,377
In Sweden June 7, 1928

7 Claims. (Cl. 235—60)

This application is a continuation-in-part of application Serial No. 368,144 filed June 3, 1929, and of a prior continuation-in-part of said application, Serial No. 36,030 filed August 13, 1935, and, as to common subject matter, relates back to said applications Serial Nos. 368,144 and 36,030 for all dates and rights incident to the filing thereof and the filing of foreign applications corresponding thereto.

This invention refers to book-keeping and accounting machines and the like and involves a new principle of effecting the control of balancing totalizers by their operating means.

The invention has for its principal object the provision of a machine for maintaining an account of a plurality of related factors. For this purpose the machine comprises a plurality of adding and subtracting totalizers and further operating means operable both to select a plurality of said totalizers for actuation and simultaneously to select the sense in which each of said totalizers shall be actuated.

Another object of the invention is to provide a machine of the kind described comprising means for setting the totalizers for actuation in such way that the totalizers which in a certain case are to be combined for some purpose in one and the same operation of the machine, are directed, in all respects, from one single operating means covering the whole operation, so that, for each cycle of the machine, one operating means only has to be manipulated once, besides the depressing of the numeral keys.

Another object of the present invention in its preferred embodiment is more particularly to provide a machine for financial control, book-balancing and book-keeping, based on an improved accounting method.

According to this method every commercial enterprise or business activity must comprise, financially, four fundamental factors, viz. assets, liabilities, profits and losses. The different classes, into which the assets are divided, e. g. cash, stock, sundry debtors, etc. as well as the different classes of liabilities, profits and losses will be called special factors.

Business activity consists of a series of individual transactions which in fact always involve changes in the amounts of the said factors of the enterprise. The individual transaction always implies a simultaneous change (increase or decrease) of the same size in the amounts of two special factors, a fact which in the double entry book-keeping appears in such a way that every debit entry has its corresponding credit entry,

and vice versa. With logical necessity these changes in two special factors cannot occur in more than the eight following ways. (Designations used: T for assets, S for liabilities, V for profits, F for losses.)

1. A kind of loss increases (F+), whilst at the same time a kind of assets decreases (T-);
2. A kind of loss increases (F+), whilst at the same time a kind of liabilities increases (S+);
3. A kind of assets increases (T+), whilst at the same time a kind of profit increases (V+);
4. A kind of liabilities decreases (S-), whilst at the same time a kind of profit increases (V+);
5. A kind of assets increases (T+), whilst at the same time another kind of assets decreases (T-);
6. A kind of assets increases (T+), whilst at the same time a kind of liabilities increases (S+);
7. A kind of liabilities decreases (S-), whilst at the same time another kind of liabilities increases (S+);
8. A kind of liabilities decreases (S-), whilst at the same time a kind of assets decreases (T-);

The above outlined method involves (1) the analysis of the transaction to be recorded, according to one of the afore-mentioned eight combinations of the four fundamental accounts: assets, liabilities, profits and losses; (2) and also the recording of the transaction in question simultaneously four times, viz. in the debit of one account, in the credit of another account, on the voucher and in the day-list. To carry out this method the machine according to the invention is provided in this particular case with a plurality of totalizers operable for addition and subtraction, inter alia corresponding to the fundamental factors: assets, liabilities, profits and losses, and further provided with operating means to set in operative position simultaneously, in the right sense, those two of said totalizers that, according to the analysis, are to be affected by the business transaction to be recorded. Further the machine must be so constructed that in one single operation it immediately shows in totalizers the amount of the net profit or net loss and also the amounts of the assets, liabilities, profits and losses and the total sum of the amounts of the transactions registered.

Another object of the present invention is to provide a machine, the functioning of which is based on aforesaid method, by means of which machine the number of the economic analysis of the voucher according to said method, the date,

the controlling number and the amount of the voucher and other items can be printed simultaneously a plurality of times, for instance in the debit of one account, in the credit of another account, on the voucher and in the journal-list, thus permitting a direct book-keeping up to 100%.

Another object of the present invention is to provide a machine of the kind described, in which the said operating means for simultaneously setting the totalizers into working position, consists of one or more so-called analysing keys. If only one analysing key is used, said key should be adapted to be set in different positions so as to both select a plurality of totalizers for actuation and, simultaneously, select the sense, in which each of the totalizers thus selected shall be actuated. Preferably, however, the number of analysing keys is equal to the number of totalizer combinations, i. e. for the embodiment shown as many as the classes of transactions, i. e. eight. It is further possible that the said operating means consists of electromagnets instead of keys, and perforated cards and brushes may also be utilized as operating means, in which either the cards or the brushes are movable relative to the other members.

The machine may be provided with one or more adding totalizers, one of which, the so-called chronological total amount totalizer, indicates the sum of all items recorded. Further the machine may be provided with a printing device printing automatically, that is to say without the medium of any key, the number of the items in chronological order which, of course, facilitates the control.

Further the machine may be provided with operating means to restore the machine in any desired position. If an item has been erroneously recorded and printed the totalizers can by the said operating means be restored to the positions which they assumed, before the erroneous item was set up and printed. This restoring means may consist of a single key, especially when the analysing means consist of one key only, but, preferably, it comprises a row of keys adapted to set the totalizers to carry out the calculation in opposite sense to that for which the corresponding analysing keys would set said totalizer.

The present invention will now be described in detail with reference to the accompanying drawings which show a preferred embodiment of a machine according to the invention.

In the drawings:

Fig. 1 illustrates diagrammatically the principle of an improved accounting method.

Fig. 2 is a plan view of the machine in one of its preferred embodiments, various details being omitted for the sake of clearness.

Fig. 3 is a lateral view of one section of said machine.

Fig. 4 is a lateral view on an enlarged scale of the upper right-hand totalizer with appurtenant transmission gears as shown in Fig. 3 illustrating the ten transfer mechanism.

Fig. 5 is a view similar to Fig. 4 but seen from the opposite side.

Fig. 6 is a view seen from the left in Fig. 4 and from the right in Fig. 5 illustrating the denominational order of the totalizer and the corresponding transmission gear, the lowest denominational order being to the left and the highest order to the right of the figure.

Fig. 7 is a lateral view in detail of a numeral key row.

Fig. 8 is a section on the line VIII—VIII in Fig. 7.

Fig. 9 is a similar section through a pair of cooperating analysing and restoring keys.

Fig. 10 illustrates the control of the totalizers from the key-board and from the main driving shaft.

Fig. 11 is a perspective view of the connections of analysing keys with members controlling the totalizers.

Fig. 12 is a detail lateral view of a listing key and the locking means controlled thereby.

Fig. 13 is a section along the line XIII—XIII in Fig. 12 showing the key rows E, F, G and H.

Fig. 14 is a detail view of the hammer mechanism of one of the printing devices.

Fig. 15 illustrates a ten transfer mechanism of another type.

Figs. 16, 17 and 18 are views of a ten transfer mechanism of still another type.

Fig. 19 is a lateral view, partly in section, of a modification of the analysing device in which one key means only is utilized.

Fig. 20 is an end view, partly in section, of the device shown in Fig. 18 along the line XX—XX.

Fig. 21 is a plan view of the same.

Fig. 22 is a lateral view of still a further modification of the analysing device in which electromagnets are employed.

Fig. 23 is an end view, partly in section, of the device shown in Fig. 22 together with details for energizing the electromagnets, showing a top plan view of a portion of the means along the line XXIII—XXIII of Fig. 22.

Fig. 24 is a lateral view, partly in section and partly broken away, of the key means of Fig. 23.

First the principle of my new accounting method will be described in one example with reference to Fig. 1. In this figure, 1, 2, 3, 4, 5, 6, 7, and 8 designate eight analysing keys corresponding each to one of the eight business transactions as indicated to the left of the keys in accordance with the designation above referred to.

1, 2, 3, 4, 5, 6, 7 and 8
x, x', x, x', x, x', x and x

designate eight restoring keys corresponding each to the business transactions opposite to that of the corresponding analysing key as indicated to the right of said restoring keys. That is to say, key

1
x

55 for instance, represents the business transaction T+F—, because key 1 represents the business transaction F+T— and so on. Between the two rows of keys there are shown six totalizers representing in order from above and downwards the assets totalizer RA', the liabilities totalizer RB', the chronological total amount totalizer TR, the balance totalizer RC', the profit totalizer RB'' and the loss totalizer RA''. The manner in which the different analysing and restoring keys select said totalizers for actuation and simultaneously select the sense in which each of said selected totalizers shall be actuated is illustrated by way of lines drawn from the keys to the totalizers. Thus it is seen, for instance, that the analysing key 1 representing the business transaction: increase of loss and decrease of assets, that is F+T—, selects the assets totalizer RA', the loss totalizer RA'' and the balance totalizer RC', and simultaneously determines subtraction for RA', addition for RA'' and subtraction for RC'.

Further this key, as well as all other analysing keys, selects the chronological total amount totalizer TR adding all items in succession. It is of course understood that there may be more than only one such adding totalizer TR. The restoring key

1
x

selects the assets totalizer RA', the balance totalizer RC', the loss totalizer RA'' and the chronological total amount totalizer TR and simultaneously determines addition for RA' and for RC' and subtraction for RA'' in accordance with the business transaction represented by said key. In other words the analysing key 1 and the restoring key

1
x

select the same totalizers for actuation but determine the sense of calculation to be opposite each other.

Evidently, the balance totalizer RC' will only be operated for the four first kinds of business transaction, as the balance will remain unaltered after entering a business transaction of the fifth, sixth, seventh or eighth kind. Further, the analysing keys 5 and 7 and the restoring keys

5 and 7
x and x

are only connected with the chronological total amount totalizer TR, said keys representing business transactions which only cause a transfer in the assets and the liabilities accounts, respectively. In Fig. 1, said keys are shown by dotted lines to be connected with the plus side and the minus side of the assets totalizer RA' and the plus side and the minus side of the liabilities totalizer RB', respectively, as a depression of said keys will influence corresponding printing devices without influencing the corresponding totalizers.

The general arrangement of the machine

The embodiment of the machine illustrated in the drawings comprises (see especially Fig. 2) two similar machine sections A and B placed on each side of a third machine section C. The three machine sections A, B and C comprises each two adding and subtracting totalizers. For the sake of clearness the totalizers of the central section C only are shown in Fig. 2 and are designated RC', RC'', respectively, but as also the other totalizers will be referred to in the following specification, they will be termed RA', RA'' and RB', RB'' belonging to the machine sections A and B, respectively. According to Fig. 3 60 the machine section A is shown to comprise also a chronological total amount totalizer TR. Each machine section comprises further a printing device TA, TB, and TC, respectively, with appurtenant hammer mechanism SA, SB and SC, respectively. The three machine sections A, B and C are controlled by a common key-board D.

The key-board

The key-board D comprises in the embodiment shown several rows of keys, viz. reckoned from the left in Fig. 2 one series E of eight keys 1 to 3 inclusive for selecting the totalizers and their sense of calculation and corresponding to the 75

analysing keys 1 to 8 in Fig. 1, one series F of eight keys

1 to 8
x to x

5 inclusive, corresponding to the restoring keys

1 to 8
x to x

in Fig. 1, one series G of twelve keys for recording the name of the month and designated by the first three letters of the month, the keys corresponding to the months January to September being arranged in the third key row and the keys corresponding to the months October to December in the fourth key row, one series H of three keys and one series K of nine keys for recording the day of the month and designated by 1, 2, 3 and 4 to 9, respectively, and at last a plurality of rows of numeral keys proper, as a whole designated L, in the embodiment shown five rows. Further the first key row contains an additional key marked K+, the second key row an additional key marked K- and the fourth key row an additional key marked L¹. The function of these additional keys will be explained later. It should be observed that also other keys may be provided fulfilling different objects.

The transfer system from the key-board to the selector

30 The numeral keys L, the date keys H and K and the month keys G consist each of a key-rod 10 guided in the key-board frame 11 in any suitable manner and provided with a key tab 12. 35 All keys in one row co-operate with a common releasing device for an actuator rod 14 (see Figs. 7 and 8). For the sake of simplicity the different actuator rods will not be distinguished from each other but all designated by the same 40 reference number 14. Each releasing device comprises a plate 16 pivotally mounted at its opposite ends at 18 on a key-board partition 19. A spring 20 tends to hold said plate 16 in such position that its fore end is right before a downward projection 21 on the actuator rod 14, the 45 distance between said projection 21 and the fore end of the plate 16 corresponding to one tooth for the purpose to be described later on. The key rods 10 are each provided with a projection 22, and a spring 23 connects said projection with another key-board partition 24. The actuator rod 14 is at its fore end provided with a projection 25. In Figs. 7 and 8 one key is illustrated in its depressed position and, as shown, the projection 22 on the corresponding key rod 10 forms in said position a stop for the actuator rod 14 in a manner to be described later on.

During the setting operation a depressed key in each of the rows G, H, K and L is held in its depressed position by a locking bar 15 extending along the key row and provided with a pin 17 for each key rod 10, said pins 17 co-operating with shoulders 27 on the key rods 10. A spring 29 tends to move the bar 15 backwards, that is to say to the left in Fig. 7. Any depressed key is returned to starting position by a restoring rod 31 extending transversely of the key rows G, H, K, L and bearing on the rear ends of the locking bars 15, said rod 31 being supported by arms 33 pivoted on studs 35 on keyboard partitions 24. Pivoted to one of said studs 35 and rigidly connected to the corresponding arm 33 is another arm 41 (see also Fig. 3) which by a link 43 is pivoted to one end of a lever 68, the other end of which normally bears on the end

of an arm 10 secured to the rocking main shaft 100, the lever 68 being at this end provided with an inclined surface 72. Intermediate its ends the lever 68 is provided with an elongated slot 74 mounted to slide and to rock on a stud 76 secured to the machine frame. A spring 78 tends to rock the lever 68 in counter-clockwise direction (Fig. 3).

The actuator rods 14 are each actuated by a spring 26 (see Fig. 3) secured at its one end at 28 to the rod 14 and at its other end at 30 to the machine frame. The springs 26 tend to move the actuator rods backwards (to the left in Fig. 3). At their rear ends the actuator rods 14 are each pivotally connected at 32 to a toothed gear or actuator wheel 34. The gears 34 are all loosely journalled on a common shaft 36 mounted in any suitable manner in side walls 37 and 39 of the machine frame, see Fig. 2. These toothed gears 34 form the actuator of the machine and will be more fully described later.

In the embodiment shown, the third row, reckoned from the left in Fig. 2, comprises, as stated above, nine keys marked "Jan" to "Sep" and the fourth key row contains the remaining month keys "Oct," "Nov," and "Dec." These month keys in the fourth key row are coupled to the third key row and operate the actuator rod 14 of said key row which, consequently, may assume twelve different positions, the arrangement above described being chosen for the sake of symmetry.

The transfer system for the analysing keys and the restoring keys differs somewhat from that for the other keys. The key rows E and F have a common actuator rod which for the sake of convenience is also designated 14. The keys consist each of a key-rod 40 (see Figs. 3, 9 and 10) having a key tab 42 and abutting each with its lower end against one end of an angular catch 44 fulcrumed at 46 in the key-board frame in any suitable manner. A spring 48 tends to maintain the key in raised position. The catch 44 engages normally a releasing bar 50 holding said bar in lowered position against the action of a spring 52. The bar 50 is provided with three abutments 54, 56 and 58 in the order from above and downwards. Arranged above the uppermost row of abutments 54 is a restoring plate 60 normally out of engagement with said abutments 54. One edge 62 of the plate 60 forms a shaft suitably journalled in the frame at 61 and 63 and serving as swinging axle for the plate. Pivotally connected to said plate 60 at one end on the edge opposite to the shaft 62 is a link 64 extending downwards and provided at its lower end with an eye 66. Projecting into said eye 66 is the one end of lever 68 (Fig. 3).

Arranged above the second row of abutments 58 on the releasing bars 50 (see Figs. 3 and 9) is a stop bar 80 pivotally mounted in the machine frame at 82. In its normal position this stop bar 80 prevents any backward movement of the actuator rod 14 from the starting position thereof, the abutment 84 on said selector rod 14 cooperating with some play with said stop bar 80. The actuator rod 14 is arranged between the second abutment row 56 and the third abutment row 58 and is pivotally connected, in the same manner as other actuator rods 14, at its rear end at 32 to one of the actuator wheels 34 of the selector.

Extending below the key-board D (see Figs. 3 and 10) are two rows of shafts each comprising eight shafts 90 and 92, respectively. Journalled

on each of said shafts is a bell crank lever 94 and 96, respectively. The releasing bars 50 of all analysing keys 1-8 are each connected with one arm of the bell-crank lever 94 by means of a wire 98 and the releasing bars of all restoring keys

1 8
x x

are each connected with one arm of the bell-crank lever 96 by means of a similar wire 98. In order to permit transmission from the keyboard to the three machine sections, the shafts 90 and 92 extend laterally of the keyboard at both sides thereof, and for each section there are provided similar bell-crank levers 94 and 96, preferably at both sides of the unit, as is shown in Fig. 2. Arranged below the actuator wheels 34 of each machine section and at both sides thereof is a pair of bell-crank levers 102 and 104 pivotally journalled in the machine frame about spindles 110 and 112, respectively. Wires 106 connect one arm of each of the bell-cranks 94 and 96 with one arm of either a plus lever 104 or a minus lever 102 or both of the various totalizers in the three machine sections A, B and C in accordance with the business transactions represented by the corresponding analysing or restoring key (see Fig. 11). The other arms of said bell-cranks are connected to levers or bell-cranks to control the setting of the various totalizers in a manner to be described later.

When one analysing key only is used, which is adapted to be set in different positions, it may be carried out in practice as shown for instance in Figs. 19, 20 and 21 or Figs. 22, 23 and 24. In the first-named case an arm 301 is fixed to a shaft 300 pivotally mounted in the frame of the machine. The upper end of the arm 301 supports by means of a pin 302 a lever 303 having a knob 303a for handling the same. This lever is integral with two lateral arms 305 and 306 and the shaft proper 303 is made to slide in a slot 320 in the key board plate 321. The slot has branch slots 322 and 322x (see Fig. 21) extending towards each of the numerals 1 to 8 and

1 8
x x

respectively, in accordance with the scheme shown in Fig. 1. The arm 301 has a bore hole containing a spring 323 which presses a ball 304 against the lever 303 in one of three recesses on the underneath side thereof, in order to retain the lever in one of three positions, viz. either in the central position in the slot 320 or at the bottom of one of the branch slots 322 or at the bottom of one of the branch slots 322x. The arm 301 with the lever 303 may obviously be swung to and fro along the slot 320 and the lever 303 may be swung at right angles to the swinging movement of the arm 301 into one of said branch slots.

When the lever 303, which on the drawing has been shown to be in position to be swung into the slot 322 belonging to the analysing key 6 or into the slot 322x belonging to the analysing key

6
x

70 is swung to the left in Figs. 20 and 21, the arm 305 will actuate the catch 44 (Fig. 19), which releases the bar 50 by means of the spring 52, as described above, and the totalizers belonging to a business transaction of the kind 6 (T+S+) are set. When the lever is swung to the right,

the corresponding restoring operation (S-T-) will take place.

The releasing of the bars 50 may also be carried out by means of electromagnets, in which case these magnets may be energised by means of contact devices which are operated by means of a plurality of keys of the kind as shown in Figs. 2 and 3 or by means of a single key such as presently will be described in connection with Figs. 22, 23 and 24. The contact device may also consist of the well-known perforated cards co-operating with brushes, in which case either the card or the brushes are moved relative to the other member. The said electro-magnets 311 are mounted in any suitable manner, for instance by means of brackets 325, on a partition 327 of the machine frame. Each magnet has an armature 310 pivotally mounted by means of a pin 312 on the bracket 325. The free end of the armature takes the place of the catches 44 of Figs. 3, 10 and 19, that is to say it normally rests on the top of the releasing bar 50. A spring 329 tends to hold the armature in said position. The use of electromagnets brings about the advantage that the contact device or devices for energising the coils of the magnets 311 may be situated, if desired, at a distance of the machine proper, and further other machines, apparatus or mechanisms which may be required for book-balancing or other accounting purposes could be inserted in the circuits connecting the contact devices with the electromagnets 311. It is obvious that when energizing the coil 311 the armature 310 is attracted, thereby releasing the bar 50 in the manner described above and required for setting the totalizers under consideration. The contact devices may be carried out in any suitable manner, those shown in Figs. 23 and 24 consisting of pairs of contact springs 330, 331 and 332, 333. Each pair of contacts may be closed by a lever 303 similar to that shown in Fig. 20 and pivotally mounted on a swingable arm 301, or the closure may be effected by individual keys. The closure of the various circuits may, as stated above, also be effected by means of perforated cards and brushes. In the example shown the contact springs 330 and 332 are insulated by means of blocks 335 and 337, respectively, from the contact springs 331 and 333. All contacts 331 and 333 are by wires 347 electrically connected with each other and with one pole of a source of power, for instance the battery 339. Each of the contact springs 330 is connected by means of a wire 348 with one end of the coil of the pertaining electromagnet corresponding to the analysing keys 1 to 8, while the contact springs 332 are connected with the electromagnets corresponding to the restoring keys

1 8
x to x

The other end of the coil of the electromagnet 311 is connected by a wire 349 and via a contact device 343 to the opposite pole of said battery 339. The contact device 343 is adapted to be closed by a motor or starting key 345 which is purely diagrammatically shown in Fig. 23. The operation is as follows: At first the arm 301 is swung in position opposite to one of the contact devices 330, 331 or 333, 332, thereafter the lever 303 is turned, whereby the contact springs make contact, and finally the motor key 345 is depressed. By this means the pertaining electromagnet 311 is energised and the bar 50 is re-

leased, whereby the totalizers in question are prepared for actuation.

The actuator

5 As already mentioned, the actuator comprises a series of actuator wheels 34 loosely journaled on a common shaft 36 and each actuated by a spring 132 tending to rotate the wheel in clockwise direction as seen in Fig. 3. In the embodiment shown each machine section comprises twelve such actuator wheels 34, viz. reckoned from the right in Fig. 2 first five wheels corresponding to the five rows of numeral keys L, one wheel for each of the fifth row K, fourth row H and third row G, one wheel common to the second and first key rows F and E and finally three wheels belonging to a device for chronological numeration to be described later on. The shaft 36 extends transversely through the whole machine and, consequently, it is not only common to the actuator wheels 34 of one section but to the actuator wheels of all three sections A, B and C. These wheels are each in engagement with pinions 114a, 114b and 114c, respectively, (Figs. 2 and 3) and the three pinions engaging corresponding actuator wheels 34 in the three sections A, B and C are secured to a common shaft 116 suitably journaled in the machine frame. In Fig. 2 only one of these shafts is shown in order to make the drawing clearer. As shown in Fig. 2, the actuator wheels 34 of the central section C only are connected with the key-board by means of the actuator rods 14 or are controlled by the device for numeration in chronological order, but as the said wheels 34 in the central section C are each positively connected with corresponding wheels in the two lateral sections A and B by means of the pinions 114a, 114b, 114c etc. and the shafts 116, all three machine sections will, consequently, be set in uniform manner in accordance with the setting on the key-board D. As the various totalizers are normally, that is to say at the setting operation, kept out of engagement with the actuator wheels 34, said totalizers will not, of course, be set in the same manner in all three sections but only the actuator wheels of said sections.

The toothed wheels 34 are in permanent engagement with two upper groups of transmission gears 130 each group loosely journaled on a common shaft 173 (see Figs. 3 and 10). Further the actuator wheels 34 of section A which correspond to the numeral key rods L are in permanent engagement with another lower group of transmission wheels 130 loosely mounted on a similar shaft 173. An adding and subtracting totalizer is provided above each of said upper groups of transmission gears and in section A a chronological total amount totalizer TR is provided at the side of said lower transmission gears 130.

Secured to the actuator shaft 36 are pairs of arms 134 for each section, the free ends of which are connected by rods 136 extending each through one section and resting normally against one of the spokes 137 of the actuator wheels 34 thus serving as stop rods for said wheels holding them in starting position. Pivoted to one of said rods 136 is a connecting rod 138, the other end of which is movably connected with a crank 140 loosely mounted on the main driving shaft 100. Secured to said shaft 100 is an arm 142 provided with a pin 144 which is adapted to engage said crank 140, when the shaft is rocked 70 in clockwise direction. A spring 146 tends to

hold arm 140 against a stop 141 and thus to keep the stop rods 136 in engagement with the actuator wheels 34.

The totalizers

The adding and subtracting totalizers arranged above the upper groups of transmission gears 130 (see Figs. 3 and 10) comprise each a series of digit disks 150 carrying digits from 0 to 9. The digit disks 150 are each rigidly connected with a toothed gear (adding gear) 152, and the digit disks 150 and said gears 152 are loosely mounted on a common spindle 154. The gears 152 are each in permanent engagement with another gear 156 (subtracting gear) loosely mounted on a spindle 158. The spindles 154 and 158 are journaled at their ends in bridge pieces 160.

As already mentioned section A contains a chronological total amount totalizer TR (see Figs. 3 and 10) comprising a plurality of digit disks 266 loosely mounted on a spindle 264 and each rigidly connected with a toothed gear 268 adapted to co-operate with the transmission gears 130 of said totalizer in permanent engagement with the actuator wheels 34 of this section corresponding to the numeral key rows. The spindle 264 is fixed in bridge pieces 270 loosely journaled on a shaft 272 mounted in the machine frame.

All totalizers are normally held out of engagement with the respective transmission gears 130 as will be described later on.

The control of the totalizers from the key-board

The various adding and subtracting totalizers are set for addition or subtraction by means of the analysing and restoring keys (E and F) in accordance with the business transaction to be recorded. As all these totalizers RA', RA'', RB', RB'', RC' and RC'' are controlled by the bell-crank levers 102 and 104 in the same manner, it will be sufficient to describe the controlling means for one pair of said totalizers, say RA' and RA''.

The plus lever 104 (see Figs. 3 and 10) of the totalizer RA'' is connected by means of a wire 101 with one arm of a bell-crank catch lever 164 arranged below the totalizer and journaled in the machine frame at 166, said lever 164 being so arranged as to normally support the totalizer out of engagement with the corresponding transmission gears 130, the end of the spindle 158 projecting beyond the bridge piece 160 and resting on the upright arm of said bell-crank lever 164. Similar catch levers 164 and 164a, respectively, support totalizers RA' and TR out of engagement with corresponding transmission gears 130, catch 164a being connected by wires 106 to bell-cranks 94 and 96 of all analysing and restoring keys. The minus lever 102 of the totalizer RA' is connected by means of a wire 168 with a pawl 170 pivotally journaled on a pin 172 secured to the machine frame. Normally engaging said pawl is a double-armed lever 174 loosely journaled on a shaft 176 mounted in the machine frame and common to all machine sections (see Fig. 2). A spring 178 tends to rotate said lever 174 in counterclockwise direction. At its upper end the lever 174 carries the above-mentioned bridge piece 160 in which the totalizer RA' is mounted. Since the shafts 158 terminate in the bridge pieces 160, it will be seen that the selection for subtraction also selects a totalizer for operation, the wheels being moved

into engagement with the actuators 130 when bell crank 204 or 208 as the case may be is operated. A spring 180 tends to maintain the totalizers supported by the above-mentioned catch lever 164 and to turn the totalizers into engagement with the transmission gears 130, when the supporting means of the totalizers are operated by the main shaft 100 in a manner to be described. Means are provided to prevent inadvertent movement of the totalizer wheels as they move into engagement with the transmission gears, said means comprising a locking bar 161 having teeth engaging the adding wheels 152 and supported by arms 162 pivoted to the upper end of the levers 174.

The control of the totalizer from the driving shaft

Pivotedly mounted at 182 is a curved member 184 having an arm 186 and kept in the position shown in Fig. 3 by a pawl 190 against the action of a spring 188, said pawl being fulcrumed at 192. Secured to the main shaft 100 is an arm 194 (see also Fig. 10) having a roller 196 adapted to cooperate with said pawl 190. When at the end of the forward rocking movement of the main shaft 100 amounting approximately to 110° the roller 196 strikes and lifts the pawl 190, the member 184 together with its arm 186 will be released, and when at the end of the return stroke the roller 196 engages an inclined surface 198 of a projection 200 of the curved member 184, said member is again brought into engagement with the pawl 190. Movably connected with the arm 186 at its free end is a link 202, the other end of which engages one arm of a bell-crank lever 204 fulcrumed at 206. At the free end of the other arm said lever 204 is connected by means of a link 207 with one arm of a similar bell-crank lever 208 fulcrumed at 210. The levers 204 and 208 have pins 204' that extend beneath and serve as supports for extensions 212 of the bridge supporting arms 160 of the two totalizers RA' and RA''.

Secured to the shaft 272 of the bridge pieces 270 of the chronological total amount totalizer TR is an arm 274 which by means of a link 276 is connected with an arm 278 secured to the shaft 206 of one of the releasing levers 204. The arm 274 has a sector 275, and the adjacent bridge piece 270 has a similar sector 271. Between said sectors is left a space 273. A spring 277 connects arm 274 with bridge piece 270.

The totalizers RB', RB'', RC' and RC'' are controlled by linkages similar to that illustrated in Fig. 3 for the control of the totalizers RA' and RA''.

Means are provided to restore any of the adding and subtracting totalizers when the totalizer is set for subtraction in a manner to be described, said means comprising an arm 214 (see Figs. 3 and 10) secured to the main shaft 100 and provided with a pin 216 engaging an elongated slot 218 in the lower end of a link 220, the upper end of which is pivotally connected with the free end of an arm 222 secured to the shaft 176 of the lever 174 of totalizer RA''. Secured to said shaft 176 is another arm 224 connected by a link 226 with a similar arm 228 secured to the shaft 176 pertaining to totalizer RA'. The arms 224 and 228 are each provided with a pin 230 bearing on one side of the lever 174. Thus, the levers 174 are normally locked by the pins 230 in the position of engagement with the pawls 170.

Ten transfer mechanism

In the ten transfer mechanism as illustrated in Fig. 3 and on an enlarged scale in Figs. 4, 5 and 6 each transmission gear 130 adapted to be brought into engagement with the totalizer wheels 152 or 156 has a twin gear 131 mounted on the same shaft 173 as gear 130 and in permanent engagement with the corresponding actuator wheel 34. A spring 175 connects the gears 130 and 131, said spring being fixed to a pin 177 on gear 131 and on another pin 179 fixed to gear 130 and engaging an arcuate slot 181 in gear 131. The spring 175 tends to rock gear 130 in clockwise direction as seen in Fig. 4 and, consequently, in counter-clockwise direction as seen in Fig. 5. Gear 131 has another arcuate slot 185 and gear 130 has a pin 183 engaging said slot.

Rigidly connected with each adding and subtracting totalizer wheel 152 and 156 is a disk having a tooth 187 and 189, respectively, right before the zero tooth of the totalizer wheels. Loosely mounted on a shaft 191 is a ten transfer pawl in the form of a bell-crank lever having one of its arms 193 shaped to form a trip 195 adapted to co-operate with the teeth 187 or 189 of the next lower denominational order, whereas the other arm 197 of the pawl is adapted to co-operate with the pin 183.

A projection 251 on pawl 193, 197 carries a pin 199 adapted alternately to engage one of two recesses 201 and 203 in a locking lever 205 rockable on a shaft 209. A spring 211 connects the ten transfer pawl with lever 205 and tends to keep the pin 199 in mesh with either of said recesses. Secured to shaft 191 is a restoring arm 213 having its free curved end adapted to co-operate with pin 183. In starting position the angular distance between the ends of the arms 197 and 213 correspond to one tooth. Secured to shaft 191 at opposite sides of the totalizer are arms 215 the free ends of which are connected by a rod 217 adapted to engage the locking levers 205.

The ten transfer mechanism is restored to starting position by the following mechanism (see especially Fig. 10).

Secured to the driving shaft 100 for each section of the machine is an arm 221 having a pin 223 adapted to co-operate with a catch 225 pivoted to one arm of a bell-crank lever 227 fulcrumed at 229. A spring 231 tends to keep said catch 225 in engagement with a stop 233 on lever 227 and the latter in engagement with a stop 235 on the machine frame. A link 237 connects the other arm of lever 227 with a bell-crank lever 239 fulcrumed at 241 and having its other arm connected by a link 243 with an arm 245 secured to shaft 191. A link 247 connects said arm 245 with a bell-crank lever 248 fixed to the shaft 191 of the ten transfer mechanism of totalizer RA', and another link 249 connects said bell-crank lever 248 with a bell-crank lever 250 fixed to the shaft 191 of the ten transfer mechanism of the total amount totalizer TR.

The printing devices

Each actuator wheel 34 (see Fig. 3) is provided with a toothed segment 232 which in the embodiment shown has a smaller diameter than the wheel 34 proper. Engaging said segment 232 is another toothed segment 234 rockably mounted to a shaft 236. It is evident that, if desired, the toothed segment 234 may instead engage the toothed wheel 34. Secured to this segment 234 is an angularly shaped arm 238 pivotally con-

nected at its free end by means of a link 240 to a projection 242 on a type carrier 244 provided at its upper end with types 246 in the form of small pins extending through and beyond the type carrier 244 at both sides thereof. At their one end the pins 246 carry numerals from 0 to 9 in the order from above and downwards except the pins of the type carrier corresponding to the month keys which carry designations from "Jan" to "Dec" and the pins of the type carrier corresponding to the fourth key row, which carry only the numerals 1, 2 and 3.

The fore ends of the type pins 246 and 250 are adapted to co-operate with a hammer mechanism designated in Figs. 2 and 3 by SA, SB, SC and SD, respectively. As all these hammer mechanisms are identical and controlled by the main driving shaft in the same manner, it will be sufficient to describe one mechanism, for instance SC, reference being had to Fig. 3 and especially to Fig. 14.

The hammer mechanism comprises hammers 350 journaled on a shaft 351. The hub of each hammer has an arm 352 and a projection 353 arranged diametrically to each other. Arm 352 is actuated by a spring 354 tending to move the hammer 350 in counter-clockwise direction. Further the hammer 350 is provided with a pin 355 cooperating with a pawl 356, all said pawls being fixed to a common locking bar 357 which is rotatably mounted on a shaft 358 and to which the springs 354 are secured. Connected with the locking bar 357 is an arm 359 riding on a cam disk 360 mounted on shaft 351 and provided with a projection 361. Secured to said shaft 351 are further two disks, one of which may consist of disk 360 and which are connected by a bridge 362. Shaft 351 carries also an arm 363 which by a link 364 is pivotally connected with an arm 365 secured to a shaft 366. Fixed to this shaft 366 is another arm 367 which by a link 368 is pivotally connected as at 382 with a lever 369 rockable on a stud 370 and adapted to be actuated and rotated in clockwise direction by a roller 371 on an arm 372 fixed to the main driving shaft 100 (see Fig. 3).

Levers 373, one for each type carrier 244, are rotatably mounted on a shaft 374 and have their one arm 375 formed as a hook 376 which in starting position of the type carrier is right in front of a recess 377 in the carrier, whereas the other arm 378 of the lever 373 is actuated by a spring 379 tending to rock the lever in clockwise direction. The upper end of arm 378 is adapted to be rocked below the projection 353 in order to lock the corresponding hammer 350.

All the printing devices are controlled by one and the same operating means 369, 372, the links 364 of the hammer mechanisms SA and SB of the two lateral printing devices TA and TB being by arms 380 connected to a shaft 383 mounted in the machine frame, said arms 380 being by links 381 pivoted to the stud 382 on the operating lever 369. The platens of the printing mechanisms of the left hand and right hand sections are shown in Fig. 3 and designated PA and PC, respectively.

An additional printing device is provided, by means of which the item recorded can be registered on the day-list on which the items are printed in chronological order without respect to the mode of calculation. This printing device TD is diagrammatically shown in Fig. 3 and consists of type pins 250 arranged in the lower part of the type carriers 244 in the same manner as in the printing device TA. The printing is per-

formed on a paper on the platen PD, the paper being wound from a roll 252 onto a roll 254.

The device for chronological numeration

As stated above, the actuator of each machine section contains a plurality of actuator wheels 34 belonging to a device for chronological numeration. In the embodiment shown these wheels are the three first ones reckoned from the left in Fig. 2. These wheels 34 engage each a pinion 256 (see Fig. 3) loosely journalled on a common shaft 258. Secured to each of the pinions 256 is a larger gear 260. The actuator wheels 34 associated with this device do not, of course, co-operate with any totalizer wheels but each with a printing unit. The gear wheels 260 and ten transfer gears 261 engaging same as well as the pinions 256 form together a counter which is fed one step for each recorded business transaction. The counter may be of the well-known "Veeder" type but in the drawings a counter is shown of the type described in my co-pending application for Letters Patent filed on September 25th, 1937, Serial No. 165,775 which application is referred to with regard to the structure and operation of the counter. For the sake of explanation of the operation of the counter in combination with the machine according to this invention it should only be mentioned that the means for stepwisely advancing the counter comprises a locking member in the form of a catch 385 adapted to set said feeding means out of function as will be explained later.

The mode of operation of the machine

In order to explain the mode of operation of the machine it is assumed that of the two totalizers of the left hand section the totalizer RA' records "assets" and the totalizer RA" "loss," that of the two totalizers of the right hand section the totalizer RB' records "liabilities" and the totalizer RB" "profit" and that the rear totalizer RC' of the central section records the balance. It is further assumed that the business transaction to be recorded is the following:

On the 6th May note-paper is bought in cash for \$7.25. The cashier analyses this business transaction correctly to be of the first class (F+T-, Fig. 1) and writes a number "1" on the voucher. When the operator of the machine gets the voucher in his hand and has to record the business transaction, he depresses the following keys reckoned from the left in Fig. 2: in the first row E the key 1, in the third row F the key "May," in the fifth row K the key 6, in the eighth row the key 7, in the ninth row the key 2 and in the tenth row the key 5.

On depressing the key 1 in the first row E which key is connected with the minus lever 102 of the rear totalizer RA' (assets=T-) of the left hand section A, the plus lever 104 of the fore totalizer RA" (loss=F+) of the same section, with the minus lever 102 of the balance totalizer RC' and with the bell-crank 164a pertaining to the total amount totalizer TR in accordance with the diagram shown in Fig. 1, the catch 44 releases the bar 50 which moves upwards under the action of the spring 52 whereby on the one hand the abutment 56 on said bar swings the stop bar 80 out of engagement with the projection 84 of the actuator rod 14 and on the other hand the abutment 58 forms a stop for the actuator rod 14 on the following backward movement of same. The actuator rod 14

cannot yet move backwards being prevented therefrom by its connection with the corresponding actuator wheel 34 which in turn is locked by the stop rod 136. When the bar 50 moves upwards, the corresponding bell-crank levers 94 and 96 are turned in counter-clockwise direction as seen in Figs. 3 and 10 causing the levers 102 and 104 to turn in the same direction. The turning of the minus levers 102 of the rear totalizer RA of the left hand section A and the rear totalizer RC' of the central section C results in the pawls 170 releasing the double-armed levers 174 which are now free to swing in counter-clockwise direction under the action of the springs 178. This swinging is, however, prevented by the engagement of said levers 174 with the pin 230 on the arm 228. By the turning of the plus lever 164 of the fore totalizer RA" of the left hand section A the supporting bell-crank lever 164 of said totalizer will be swung in clockwise direction out of engagement with the end of the spindle 154, this totalizer being, however, still supported by the bridge piece 160 resting with its extension 212 on one arm of the bell crank lever 208. When the bell-crank 94 is rocked, the bell-crank 164a resting against the spindle 264 of the totalizer TR will also be rocked leaving the bridge pieces 270 of the totalizer TR free to move to the right (Fig. 3). This movement, however, is still prevented by the sector 275 bearing on the sector 271. When later the bell-crank 204 is rocked in clockwise direction, the link 276 and thus the arm 274 will be lifted, so that the spring 277 can draw the wheels of the totalizer TR into engagement with the transmission gears 130.

On depressing the key "May" the corresponding key-rod 10 (see Figs. 7 and 8) moves downwards releasing the corresponding actuator rod 14 from engagement with the locking plate 16 and forming with its lug 22 a stop for the following backward movement of the actuator rod 14. In the same manner the depression of the keys "6," "7," "2" and "5" will release the corresponding actuator rods 14, the different key-rods 10 forming stops for said rods 14 on the following backward movement thereof. For the same reason, as stated above with regard to the analysing key actuator rod 14, these rods cannot move backward, before the main shaft 100 is actuated. The machine is now set for the record in question.

Before actuating the main shaft, the voucher and two account cards are inserted in the printing devices TC, TA and TB, respectively, the account cards being, of course, selected in accordance with the class of business transaction to be recorded. In the example referred to the two accounts which are influenced by the business transaction referred to are the cash account and the expense account.

When now the main shaft 100 is rocked in clockwise direction, the arm 214 secured to the shaft is swung in the same direction, the pin 216 on said arm sliding in the slot 218 in the link 220 which thus is free to move upwards permitting the double-armed levers 174 of the totalizers RA' and RC' to swing in the same direction under the action of the springs 178 causing the totalizers RA' and RC' to swing in the same direction through such an angle that the subtraction gears 156 of the totalizers come right above the corresponding transmission gears 130.

the projection 212 of the supporting bridge piece 160 riding on the pin 204' on the supporting lever 204. During this movement the lever 174 turns the arms 224 and 228 in counter-clockwise direction, thus lifting the link 220. Simultaneously the arm 142 secured to the main shaft 100 is turned in clockwise direction, and after a given angle of rotation pin 144 on said arm 142 strikes crank 140 turning said crank in the same direction so that the connecting rod 138 moves the stop bars 136 out of engagement with the actuator wheels, and the actuator wheels 34 are free to turn an angle corresponding to ten teeth of the totalizer wheels. Thereby the actuator rods 14 which correspond to keys that have been actuated, are free to move backwards, that is to say in the example referred to the actuator rods 14 corresponding to the first, third, fifth, eighth, ninth and tenth key rows.

As already described the stopping plates 16 of the key rows G, H, K and L are so arranged in relation to the actuator rods 14 determining the setting of the actuator wheels 34 that said actuator wheels are always rotated through one tooth even when the corresponding stopping plates 16 have not been actuated, that is to say the actuator wheels corresponding to non-actuated key rows are turned one tooth and those corresponding to actuated key rows are turned an additional tooth beyond the angle corresponding to the position of the depressed key rod 10. As will be described later this additional movement through one tooth is necessary only for the operation of the ten transfer means as shown in Figs. 4, 5 and 6, that is to say only for the actuator rods of the numeral key rows L but not for those of the key rows G, H, K, although the arrangement has been adopted also for the last-mentioned key rows for the sake of symmetry.

In agreement herewith and with the example referred to the actuator wheels 34 appurtenant to depressed keys will be turned in the following manner reckoned from the left in Fig. 2: the first gear one tooth (analysing key 1), the third gear six teeth (month May), the fifth gear seven teeth (the day 6) and the eighth, ninth and tenth gears, eight, three and six teeth (\$7.25), respectively. Further rotation of the gears influencing the analysing key actuator wheel is prevented by the actuator rod 14 abutting against the abutment 58 on the releasing rod 50 of the key 1. Also further rotation of those influencing the other gears is prevented by the actuator rods 14 abutting against the end of the key-rod 10 of the depressed keys. All actuator wheels 34 corresponding to key rows which do not contain any depressed key are turned one tooth, until the corresponding actuator rods strike the locking plates 16. The actuator wheels which have been actuated have, consequently, in order from the left in Fig. 2 been set on "1", "May", "6", "7", "2" and "5" and the transmission gears 130 of said gears are set in the same manner.

During the forward stroke of the main shaft 100 the counter 256, 260 for chronological numeration has been moved forward one step, so that the corresponding gears 34 and type rods 244 have been set on a number one unit higher than the preceding number. For the sake of illustration it may be assumed that the preceding number was 125 and the new number, consequently, 126.

On account of the positive connection between

the actuator wheels 34 in the three sections of the machine the setting of said wheels in the central section C causes a corresponding setting of the wheels in the lateral sections A and B. By means of the toothed sectors 234 and the linkages 238, 240 the setting of the actuator wheels 34 is transferred to the corresponding type carriers 244 of the four printing devices TA, TB, TC and TD, and when in the manner to be described the hammer mechanisms SA, SB, SC and SD are released at the end of the forward stroke or immediately before, the following entry "126 1 May 6 7.25" will be printed in credit on the cash account card, in debit on the expense account card, on the voucher and on the day-list.

The release of the hammer mechanisms will be described with reference to the mechanism SC as shown in Figs. 3 and 14.

At the end of the forward stroke of the driving shaft 100 roller 371 on arm 372 is turned into engagement with lever 369 rocking same in clockwise direction. This movement is transferred by the linkage 368—364 to arm 363 which together with shaft 351 is rocked in counter-clockwise direction. Thereby bridge 362 releases all pawls 353 but the hammers 350 are still locked by pawls 356. After continued rotation of bridge 362 levers 373 are also released. For all such type carriers 244 which have not been actuated this results in the levers 373 with their upper arms 378 being turned below the corresponding pawls 353 under the action of springs 379, the lower arms 376 of the levers 373 engaging the recesses 377 in the type carriers 244. This results in the corresponding hammers 350 being locked. On the contrary for such carriers 244 which correspond to actuated actuator wheels 34 and, thus, have been moved upwardly this rocking of levers 373 is prevented by the recesses 377 in the type carriers no longer lying right in front of arms 376. Consequently, the hammers 350 of these type carriers are not locked by levers 373. When on continued rotation of shaft 351 cam disk 366 strikes arm 358 locking bar 357 is rocked in counter-clockwise direction causing the hammers to be released from their engagement by the pawls 356. Such hammers 350 which are not locked by levers 373 are now wholly free and turned by springs 354 in counter-clockwise direction striking the types 246 which are in printing position.

All the totalizers are still out of engagement with the transmission gears 130, totalizers RA', RA'' and RC' by being supported by the pins 204a on the locking levers 204, totalizer TR on account of the connection of its arm 274 with the arm 278 and all other totalizers by being supported by corresponding supporting bell-crank levers 164. Immediately before the end of the forward stroke of the main shaft 100 the roller 196 on the arm 194 strikes the pawl 190, thus releasing the member 184 with its arm 186 which swings downwards under the action of the spring 188, thereby swinging the levers 204 in clockwise direction. The totalizers supported by the supporting levers 164 remain unactuated, whereas the totalizers RA', RA'' and RC' loose their supports and fall down and totalizer TR is swung into engagement with the transmission gears 130. In the example referred to the subtraction gears 156 of the totalizer RA', the addition gears 152 of the totalizer RA'', the subtraction gears 156 of the totalizer RC' and the gears 268 of the totalizer TR will thus be brought into engagement with the transmission gears 130, said transmission gears 130 having been set during the

setting of the selector. When now the main shaft 100 with the arm 142 allows the crank 140 to carry out its return stroke under the action of the spring 146 nothing occurs in the example referred to, before the arm 134 secured to the actuator shaft 36 has been turned through an angle corresponding to two teeth, the stop bars 136 abutting then against a spoke 137 of the gear 34 corresponding to the figure "7" which gear will then partake in the following rotation. When the arm 134 turns further, through an angle equivalent to one tooth of the gear 34, the gear 34 corresponding to date number "6" is brought into position for engagement. After a further rotation equivalent to one tooth, the gear 34 corresponding to "May" and that corresponding to the figure "5" are brought into position for engagement. When three teeth remain, the gear corresponding to the figure "2" will be brought into position for engagement. During this rotation the corresponding gears in the totalizers RA', RA'', RC' and TR will be turned through corresponding angles by the transmission gears 130. Thus, at the end of the return stroke of the main shaft 100 \$7.25 have been subtracted from the amounts in the totalizers RA' and RC' and added to the amounts in the totalizers RA'' and TR.

Near the end of the return stroke the roller 196 on the arm 194 abuts against the inclined surface 198 on the projection 200 of the curved member 184 causing the link 202 to turn the levers 204 in counter-clockwise direction whereby the actuated totalizers RA', RA'' and RC' are raised and the totalizer TR is swung out of engagement with the transmission gears 130. Thereby the totalizers RA'' and TR are returned to normal positions, but the totalizers RA' and RC' are still in subtraction positions. They are returned to normal positions by the pin 216 on the arm 214 abutting against the lower end of the slot 218 in the link 220 at the end of the return stroke, whereby the link 220 is moved downwards swinging by means of the pins 230 the actuated levers 174 of the totalizers RA' and RC' set for subtraction in clockwise direction into engagement with the pawls 170 thus returning said totalizers into normal position.

At the end of the return stroke the arm 190 (Fig. 3) secured to the main shaft 100 is swung into engagement with the inclined surface 72 on the lever 68 turning said lever in clockwise direction whereby the end of said lever engaging links 64 and 43 is lowered. The downward movement of link 64 causes the restoring plate 56 to be turned into engagement with the abutment 54 on the releasing bar 58 of the actuated analysing key 1 (see Figs. 3 and 9), said bar being thereby lowered against the action of spring 52 into engagement with the spring-actuated catch 44 which raises the key into normal position. The downward movement of link 43 causes the restoring bar 15 to be moved to the right in Figs. 3 and 7 causing the depressed keys in the key rows G, H, K and L to be raised into starting position under the action of the springs 23.

Now the machine is restored to normal position and a new business transaction can be immediately recorded.

Ten transfer in a totalizer is effected in the following manner (see especially Figs. 4, 5 and 6). The above said additional movement of the actuator rods 14 and additional rotation of the corresponding actuator wheels 34 through one tooth occurs at the end of the return stroke.

This rotation is transferred only to the gears 131 in mesh with the actuator wheels but not to the wheels 130. This motion of gear 131 is permitted as said gear is capable of being turned one tooth independent of the gear 130 on account of the pin and slot connection 183, 185. Consequently, the correct setting of the actuator wheels 34 determined by the depression of the numerical keys is transferred to gears 130 but not the additional tooth.

When during the return stroke of the machine the amount set up is transferred to the totalizer and a ten transfer is to take place, that is to say when a totalizer wheel passes from nine to zero in counterclockwise direction as seen in Figs. 3 and 4, the tooth 187 or 189 on such a wheel presses down the arm 193 of the ten transfer pawl 193, 197 corresponding to said totalizer wheel. This causes the other arm 197 of said pawl to move out of the path of the pin 183 of the gear 130 of the next higher order. During this rocking movement of the ten transfer pawl the pin 199 which was in engagement with the recess 201 in lever 205 is moved into the recess 203, spring 211 locking the pawl in this position.

When the actuator wheels are moved through the additional tooth at the end of the return stroke, this movement is imparted to all of the gears 131 but, for each order in which no tens transfer is to take place, the gear 131 is locked against the additional tooth movement by the engagement of its pin 183 with the end of the tens transfer pawl 197 of the next lower order, and the spring 175 is tensioned as the gear 130 moves a step further than the associated gear 130. In those transmission gears in which a tens transfer is to take place the arm 197 of the ten transfer pawl of the next lower order has been rocked out of the path of pin 183 and the gear 130 participates in the rotation of its associated gear 131 through the addition step or one-tooth displacement, thus effecting a tens transfer to the associated totalizer wheel. Consequently, at the end of the return stroke of the machine, gears 130, 131 in which ten transfer has taken place are not in starting position. The restoring of said gears into starting position is effected at the beginning of the next machine stroke in the following manner.

Immediately at the beginning of the rotation of the driving shaft 100 during the next machine stroke arm 221 rocks catch 225 in counter-clockwise direction (see Fig. 10) causing lever 227 to be rocked in the same direction. Thereby link 237 is moved downwardly rocking bell-crank lever 239 in clockwise direction. This movement is transferred by link 243 and arm 245 to shaft 131 which is rocked in clockwise direction as seen in Figs. 3 and 4 and in counter-clockwise direction as seen in Fig. 5. Thereby the curved end of restoring arm 213 secured to said shaft 131 presses down pin 183 and simultaneously rod 217 releases locking lever 205 which by means of spring 211 rocks the ten transfer pawl 193, 197 in counterclockwise direction as seen in Fig. 4 and in clockwise direction as seen in Fig. 5 causing pin 189 on said pawl to move from recess 203 into recess 201 and arm 197 of the pawl to lock pin 183. Now all transmission gears 130, 131 as well as all other ten transfer members are restored to starting position.

Fig. 15 illustrates how a ten transfer mechanism of conventional type disclosed in the Burrough's Patent No. 504,963 can easily be applied to the present machine. Parts in this figure and

in Figs. 4, 5 and 6 which have the same object and operation are designated by the same reference numerals.

The transmission gears 130 and 131 are shaped as sectors connected with each other by the spring 175 and by the pin and slot connection 183, 185 as in the previous embodiment. Here the arms 193 and 197 of the ten transfer pawl are formed as separate parts and pivoted on shaft 191. The projection 251 on arm 193 cooperates with a recess in a stop member 390 on locking lever 205 fulcrumed at 209. Spring 211 tends to keep stop member 390 into engagement with the projection 251. Arm 197 is influenced by a spring 391 which tends to keep the arm in engagement with a shoulder 392 on lever 205. Another spring 393 tends to keep arm 193 in raised position. A rod 394 engages recesses in the arms 193 and 197 to control the movements thereof. Arms 215 supporting between them the returning rod 217 is fixed to shaft 209 instead of shaft 191 as in the previous embodiment. The mechanism for returning the ten transfer mechanism to initial position is the same as in the previous embodiment except that arm 245 is fixed to shaft 209 instead of to shaft 191.

When the totalizer wheels pass from nine to zero, the tooth 187 or 189 will abut against the trip 195 to rock the transfer arm 193. Thereby the projection 251 will be disengaged from stop member 390 which causes locking lever 205 to be released which arm influenced by spring 211 slides along the projection 251 and moves arm 197 from engagement with pin 183 through the intermediary of shoulder 392. By this means the tooth sector 130 is allowed to move one additional step, whereby the ten transfer is performed.

When at the beginning of the forward stroke link 237 is drawn downwardly as described above, this movement is transferred by bell-crank lever 239 and link 243 to arm 245 which is rocked in counter-clockwise direction together with arms 215. Thereby the returning rod 217 rocks lever 205 in counter-clockwise direction. When during this movement stop member 390 slides from the extreme point of projection 251 on the transfer arm 193 this arm 193 is raised by spring 393, so that the projection 251 can snap into the recess in the stop member 390. Arm 197 is returned to its initial position by means of spring 391 upon the gear 131 having been turned one tooth and the pin 183 has moved past the lever, which is effected during the next forward stroke when the transmission gear 131 is set by the actuator wheel 34.

Figs. 16, 17 and 18 illustrate how a ten transfer mechanism of another conventional type disclosed in Patent No. 1,853,053 can be easily applied to the present machine.

This transfer mechanism includes a plurality of toothed transfer segments 400 pivoted on a shaft 401 carried by side plates 402 (see Fig. 17), there being one transfer segment for each pair of toothed gears 152, 156. The transfer segment 400 is normally held in the position shown in Fig. 16 by the engagement of a lateral lug 402 on an arm 403 of the segment in a notch 404 in a bell-crank detent 405 which is pivoted on a shaft 406 and urged in clockwise direction by the spring 407. The bell-crank detent 405 is controlled by the gear 152 of next lower order than the one with which the transfer segment engages. An arm 408 of the detent 405 extends above a pivoted tripping pawl 410 having a tooth-like projection 411 adapted to be engaged by a broad

tooth 412 on the gear 152. The tripping pawl 410 is pivoted on a shaft 414 carried by the frame bridges 160 of the totalizer so that the pawl moves with the totalizer as it is moved into and out of engagement with the transmission gears 130, and it is urged in a counter-clockwise direction by a spring 415, one end of which is connected to the tail of the pawl and the other end of which is connected to a latch 416 pivoted on the spindle 158. A lateral projection 420 is formed on the pawl 410 for engagement with a shoulder 421 on the latch 416 which latches the pawl in raised position under certain conditions hereinafter explained.

For the purpose of carrying when the totalizer is performing addition the transfer segments 400 are normally urged in a clockwise direction by springs 422 connected at one end to the arms 403 of the segments and at their other ends to a rod 423 carried by a cross bar 424 of a bail 425 pivoted as at 426.

A restoring bail for the segments is provided comprising a cross shaft 428 carried by arms 430 (see Fig. 17) pivoted on a rocking yoke 431, 432 as at 433, said yoke being fixed to a rock shaft 434 pivoted in the side arms 402. This bail moves in slots 435 in the side plates 402 and between the extending arms 436 of the transfer segment from the position between the narrow opening between said arms to the wider opening between them. As it moves to the right it engages the upper arm 436 of the segment and cams it counter-clockwise to normal position, the parts being proportioned so that the segment is moved sufficiently to ensure that the detent 405 will catch on the lug 402.

When one of the gears 152 is rotated from its "9" position to its "0" position the wide tooth 412 on the gear engages the projection 411 on the tripping pawl 410 and cams it upwardly to a position in which the pawl is latched in place by the latch 416 which moves the shoulder 421 beneath the lug 420. When the totalizer is moved upwardly out of engagement with the transmission gears 130 it carries the tripping pawl 405 with it and the upper side of the pawl, engaging the arm 408, moves the detent 405 counter-clockwise and releases the transfer segment 400 (engagement 402, 404) which thereupon is moved by the spring 422 a distance sufficient to move the gear 152 that engages it one tooth. In this manner the transfer mechanism is released for operation by the movement of the totalizer into engagement with the transfer mechanism. In moving the totalizer upwardly the cam plate 431, 432 is rocked clockwise in the manner to be described and moves the restoring bail 428 to the left into the position in Figs. 16 and 17 in the wide space between the arms 436 of the transfer segment which permits the segment to turn on its pivot 401 without interference from the restoring bail. The bail 428 acts as a limit stop for the segment to limit its movement to an amount just sufficient to move its gear one tooth. As the bail moves to the left, it contacts the ends of all the latches 416 and swings them out of engagement with the lugs 420 on the tripping pawls 405, whereupon these pawls are restored to normal position by the springs 415.

The transfer mechanism is restored to normal when the totalizer is next moved into engagement with the transmission gears 130. As this movement occurs the bail 428 is moved to the right in Fig. 16 and it engages the upper arms

436 of the transfer segments 400 to cam them counter-clockwise to restore all of the tripped segments to normal after the gears 152 have been moved out of engagement with the segments. The segments are then latched in position by the 5 detents 405 the notches 404 of which snap over the lateral lugs 402 on the segments.

Each of the broad teeth 411 on the tripping pawls 410 is shaped so that it will cam its pawl upwardly when the gear 152 is moving in either direction. In other words, the pawls are cammed upwardly, not only when the gears 152 move from "9" to "0" but also when they move from "0" to "9". Accordingly the transfer mechanism is set for ten transfer in subtraction in the same manner as in addition. The carry is also completed in the same general way—that is, when the gears 156 are moved out of engagement with the transmission gears 130 the tripping pawls 410 move the detents 405 to release 10 the transfer segments. However, in order to effect a borrow, it is necessary that the transfer segments move in opposite direction to that in which they move for effecting a carry. This reversal of movement is achieved by changing the 15 effective direction of the action of the springs 422. The pivoted bail 425 is swung from the position shown in Fig. 16 to that shown in Fig. 18 so that, when the transfer segments are released, the springs move them counter-clockwise 20 instead of clockwise as they are moved when the parts are in the conditions shown in Fig. 16. Accordingly, when the transfer segments are released, those that have been tripped are moved to borrow a unit from a gear 152 of higher order 25 for a gear of lower order.

The side plates 402 which carry the whole transfer mechanism are pivoted on a shaft 440 which corresponds to the pivoted connection between the bridge 160 and the lever 174 in Fig. 3. 30 When the totalizer is swung counter-clockwise to be conditioned for subtraction as described above the side plates 402 are guided by the shaft 406 which carry the bell-crank detents 405 engaging slots 441 in the machine frame. A spring 442 is connected at one end to an upstanding lug 443 of the machine frame and at its other end (at 444) to an arm of a cam plate 445 pivoted (at 446) to an arm 447 pivoted (at 448) on the side plate 402 and having a slotted end engaging 35 side plate 402 and having a slotted end engaging over a stud 450 on the end of the bail 425. A spring 451 connects the cam plate 431 with the side plate 402.

Fig. 17 shows the parts, when the totalizer is in raised position and conditioned for addition. When the totalizer is lowered into engagement with the transmission gears 130, the cam plate 431 is swung counterclockwise under the action of the spring 451, a slot 452 in the cam plate 431 limiting this swinging motion. During the following upward movement of the totalizer ten transfer occurs in the manner above described, the cam plate swinging clockwise back to the position shown in Fig. 17.

The automatic conditioning of the transfer mechanism for subtraction is accomplished, when the totalizer is swung counter-clockwise to be conditioned for subtraction as described above. During this swinging motion the side plates 402 slide in the slots 441, the spring 442 which at its upper end is secured to the machine frame being moved across the pivot 446 of the cam plate 445 so that the spring then moves said plate counter-clockwise into the position in which its shoulder 453 is beneath a stud 454 car-

ried by the cam plate. When the totalizer is then lowered into engagement with the intermediate gears 130 and the cam plate 431 is rocked counter-clockwise the stud 454 engages the shoulder 453 and moves the cam plate 445 with it downwardly causing by the engagement of arm 447 with the stud 450 the bail 425 to be rocked from the position shown in Fig. 16 to that of Fig. 18 thereby conditioning the transfer mechanism to effect a borrow instead of a carry. This action takes place automatically as the totalizer is operated after being conditioned for subtraction. During the following upward movement of the totalizer the cam plate 431 is rocked clockwise, whereas all other parts maintain their positions. Ten transfer is effected in the same manner as in addition. When the totalizer is restored to normal during the return stroke of the machine nothing occurs except that the spring 442 is moved across the pivot 446 of the cam plate 445 which thereupon is rocked clockwise while maintaining its lowered position. The hook-shaped end 455 of the cam is then above a stud 456 on the cam plate 431. When the totalizer is again conditioned for subtraction, this results only in the cam plate 445 being rocked counter-clockwise to the position in which its shoulder 453 is beneath the stud 454, whereas the relative positions of all other parts remain unchanged.

When the totalizer is conditioned for addition after having been used for subtraction the transfer mechanism is restored to effect a carry, when the totalizer is lowered into engagement with the transmission gears 130. When during this movement the cam plate 431 is rocked counter-clockwise stud 456 engages the hook-shaped end 455 of the cam plate 445 and moves said cam plate with it upwardly causing by the engagement of the arm 447 with the stud 450 the bail to be rocked from the position shown in Fig. 18 to that of Fig. 16 which automatically conditions the transfer mechanism to effect a carry instead of a borrow.

If a business transaction has been erroneously recorded and printed in the machine this can easily be corrected by using the so called restoring keys

1 to 8
x x

If in the example referred to the amount \$7.25 to be recorded has been incorrectly set up and printed in the machine, the restoring key

1
x

60 is depressed, which key, as stated above, is connected with the plus lever 104 of the totalizer RA', the minus lever 102 of the totalizer RA'', the plus lever 104 of the totalizer RC' and the chronological total amount totalizer TR. Then 65 the incorrect amount is again set up and the main shaft 100 is rocked whereby the machine will be restored into the position which it assumed before the erroneous item was set up and printed. Preferably, the printing of an item recorded by actuating a restoring key is effected in another colour than the printing of normal items, for instance by the colour ribbons of the printing devices being shifted on depressing a restoring key which 70 75 may be effected in any suitable manner.

Sometimes it may be suitable to have a control of the cash, when the business transaction has influence upon the cash account. In the embodiment shown the fore totalizer RC'' of the central section C is provided to serve this object. The totalizer RC'' is of the same type as the other totalizers and is controlled from the key board by the keys K+ and K- by means of similar means as the analysing and restoring keys (see Fig. 3). A depression of any of these two keys has no influence on the analysing and restoring keys but causes the totalizer RC'' to be set into function in any suitable manner, so that the amount is also transferred to this totalizer. Thereby the key K+ is chosen, when the cash account is debited and the key K-, when the cash account is credited.

It may likewise be desired in addition to the above-mentioned special totalizer RC'' indicating increase and decrease of the special factor, the cash, to provide one or more other totalizers indicating the increase and decrease of other special factor or factors. For this reason it is only necessary to add key or keys representing said special factor or factors and one or more corresponding totalizers for addition and subtraction which totalizers are set into working position, when the keys are depressed.

In the embodiment shown the fourth key row H contains an additional key L¹ which may be said to correspond to the "non-add" key in usual calculating machines. The object of this key is to permit use of the key-board for listing numeral values without, however, introducing those values into the totalizers. For this reason the key L¹ controls the analysing and restoring key rows E and F including the keys for the special totalizers (in the present case K+ and K-), the means to control the totalizers from the driving shaft and the type carriers of the printing devices appurtenant to the counter for chronological enumeration and to the key rows G, H and K for indicating the date in such manner that said key rows, totalizers and type carriers are locked when the L¹ key is depressed. These locking mechanisms are illustrated in Figs. 12 and 13.

The releasing bar 50 of the L¹ key is connected by a wire 98 with an arm 460 secured to a shaft 461 carrying a plurality of arms 462 which by wires 106 are connected to various members to effect the above locking. One arm 462 is connected with a crank 463 secured to a shaft 464 which carries a locking plate 465 adapted to co-operate with a shoulder 466 on such type carriers 244 which as stated above are to be locked on depressing the L¹ key. A spring 467 tends to keep the locking plate 465 out of engagement with the shoulders 466.

Another arm 462 is connected with a bell-crank lever 470 connected by a wire 471 with an arm 472 fulcrumed on the same spindle 192 as the pawl 190 above referred to, another pawl 473 being secured to said spindle 192 and adapted, in the same manner as pawl 190, to co-operate with the curved member 184. A spring 474 tends to keep the pawl 473 out of engagement with said member 184.

Still another arm 462 is connected with a bell-crank lever 475 connected by a wire 476 with the catch 385 above referred to adapted to set the counter of chronological enumeration out of function.

A spindle 480 (see Fig. 13) extends transversely of key rows E, F, G and H and is mounted in keyboard partitions, said spindle carrying an 75

arm 481 having a fork-shaped end embracing a pin 482 fixed to the key rod 40 of the L¹ key. Extending transversely of each of the key rows E and F is a sliding bar 483 and 484, respectively, said bars having recesses 485 right before lugs 486 on the key rods 40, said lugs passing normally through said recesses when the keys are depressed. Secured on the spindle 480 are two arms 487 and 488 adapted to engage notches 490 and 491 in the sliding bars 483 and 484, respectively.

When key L¹ is depressed the type carriers 244 appurtenant to the chronological counter and to the key rows G, H, K are locked by the engagement of the shoulders 466 on said type carriers by the locking plate 465. Further the curved member 184 is locked by pawl 473 so that said member still remains locked when it is released by pawl 190 at the end of the forward stroke. Further catch 385 is disengaged from the advancing means of the chronological counter. At last the depression of the L¹ key causes rotation of shaft 480 whereby the arms 487 and 488 displace the sliding bars 483 and 484 so that the recesses 485 in said bars no longer register with the lugs 486 whereby all the keys of the key rows E and F are locked.

The machine may be operated in usual manner by a handle or it may be driven by an electric motor or a motor of other kind connected to the main shaft 100 so as to impart to said shaft the desired rocking movement to and fro.

A short description of what the machine, which has been described and shown by way of an example can perform will be given below. After the machine has been set to record or indicate the business transaction to be recorded by the depression of numeral keys indicating the amount of a voucher of the business transaction referred to, keys representing the date, any additional key representing a special factor and finally the analysing key in question and by starting the machine, one obtains simultaneously the entries and results listed in the following outlines.

A. Accounting

- This is effected by the machine indicating:
1. (a) The amount of the net profit and the surplus, or
  - 50 (b) The amount of the net loss and the deficit.
  - 55 (By the amounts (a) and (b) the net result is obtained.)
  2. The amount of the assets;
  3. The amount of the liabilities.
  - 55 (By the amounts 2) and 3) the capital of the business concern is obtained.)
  - 60 4. The amount of the profits;
  5. The amount of the losses.
  - 65 (By the amounts 4) and 5) the net balance of the business concern is obtained.)

B. Book-keeping

This is effected by the analysing number, the date (month and day), the amount of the voucher and the control number of the business transaction being simultaneously printed on

- (a) The debit side of one account;
- (b) The credit side of one account;
- (c) The voucher;
- (d) The day-list (day-book).

C. Control

- This is effected by the machine indicating
1. (a) The sum of the day-list, that is to say the chronological total amount of the business concern or in other words with the sum of the amounts of booked vouchers (mathematical control);
  - (b) The sum of the entries in debit (systematical control);
  - (c) The sum of the entries in credit (systematical control); (Of course, the sums in (a), (b) and (c) are equally great.)
  2. The number of vouchers (verification control). (This number represents the order of the business transaction entered).

D. Control of the cash or other special factor

By depressing one of the keys K+ or K- the totalizer RC" indicates the change in the cash and by depressing any other additional key representing another special factor the change in said factor can be shown in totalizer.

All these indications and registrations the machine has performed in one sole operation.

It is to be observed that the invention is in no way limited to the embodiment described and shown in detail but that modifications may be made without departing from the principle of the invention. Thus for instance it is not necessary that the totalizers are selected and their sense of calculation determined in the manner described above, since the principle of the invention comprises the complex operation of various adding and subtracting totalizers by means of a single operating member. It is further possible that the toothed gears of the actuator may be replaced by any other members, such as racks. Instead of the key-board of the type shown a ten-key key-board may be used. Further it is not inevitably necessary that the machine is of the printing type. It may be only indicating. The recording of the date may be effected by hand. Further the machine may be provided with one or more correction keys for clearing the actuator of a number set up.

I claim:

1. In apparatus for maintaining an account of a plurality of related factors, the combination of a plurality of totalizers each adapted to be operated in an additive or a subtractive sense to register one of said factors, a plurality of mechanisms each operable to select at least two of said totalizers corresponding to factors affected by a transaction to be recorded and simultaneously to condition one of said selected totalizers for actuation in a desired sense and to condition the second selected totalizer for actuation in the same or alternatively in the opposite sense in accordance with the nature of the particular transaction, a manually operable control member individual to each of said selecting mechanisms, a key-board on which the number involved in said transaction may be set, and means for simultaneously registering the set number in each of the selected totalizers.

2. In apparatus for maintaining an account of a plurality of related factors, a plurality of adding and subtracting totalizers, actuator means for introducing amounts into said totalizers, and individually operable combination control keys, separate selecting means for each key and operable thereby to select a plurality of said totaliz-

ers for actuation by said means and simultaneously to determine the sense of actuation of each of the selected totalizers individually, certain of said totalizers being selected by a plurality of said separate selecting means.

3. In a calculating machine, a plurality of pairs of intermeshing sets of wheels, a frame for supporting each of said pairs, differential actuators for driving said intermeshing sets of wheels, a plurality of supports for each frame adjustable to select a given set of a pair of intermeshing sets for engagement with said differential actuators, control means, connections between said control means and said plurality of supports for the frames of two or more pairs of intermeshing sets of wheels to select predetermined pairs of intermeshing wheels for actuation and to select the particular set of wheels of each selected pair which is to engage said differential actuators, a further support for each frame, and a cyclically operated mechanism including means for displacing said further support of each selected pair to cause operative engagement of the selected set of each selected pair with the differential actuators in a predetermined time relation in a cycle.
4. In a calculating machine of the type including a plurality of totalizers having intermeshing sets of gears, the combination with means including actuator gears for introducing numeral values into a plurality of said intermeshing sets of gears, of a bridge support for each set of intermeshing gears, means mounting each bridge support for movement along a substantially vertical path towards its actuator gears to engage one set of gears or alternatively along a substantially horizontal and then a substantially vertical path to engage the other set of gears at the same circumferential portion of the actuator gears, and a plurality of selecting means each individually operable to select a plurality of bridge supports for totalizer engaging movement and simultaneously to determine the path which each selected bridge support takes in movement towards the actuator gears.

5. In a calculating machine, a plurality of pairs of intermeshing sets of wheels, differential actuators for driving said intermeshing sets of wheels, a plurality of individually operable control mechanisms each operative to select two or more of said pairs of intermeshing sets of wheels for actuation and to select the particular set of wheels of each selected pair which is to engage said differential actuators, and a cyclically operated mechanism to cause operative engagement of the selected set of each selected pair with the differential actuators.

6. In a calculating machine, a plurality of pairs of intermeshing sets of wheels, differential actuators for driving said pairs of intermeshing sets of wheels, means for each of said pairs for selecting the particular set of wheels which is to engage said differential actuators, a plurality of control members, connections between each of said members and said selecting means of two or more of said pairs of intermeshing sets of wheels to select predetermined pairs of intermeshing wheels for actuation in either direction, and a cyclically operated mechanism to cause operative engagement of the selected set of each selected pair with the differential actuators.

7. In apparatus of the type including a plurality of totalizers, each having sets of intermeshing add and subtract gears, the combination with actuating means to set up amounts in the totalizers, of a bridge support for each set

of intermeshing gears, means mounting each bridge support for movement towards said actuator means along one of two paths in accordance with the desired sense of actuation of the totalizer carried by that bridge support, said mounting means for each bridge support including mechanism mounting the bridge support for pivotal movement on an arcuate path towards said actuator means, and means supporting said mech-

anism for movement to enable the bridge support to be displaced substantially circumferentially to the actuator means prior to its pivotal movement on an arcuate path, and a plurality of individually operable means to select a plurality of bridge supports for movement and simultaneously to determine for each selected bridge support its individual path of movement.

ERNST VILHELM NYBERG.
